UNITED STATES PATENT OFFICE.

CHARLES A. HANSON AND ALBERT L. HANSON, OF MUNISING, MICHIGAN.

LAND-MARKER.

1,219,454.

Specification of Letters Patent. Patented Mar. 20, 1917.

Application filed December 3, 1915. Serial No. 64,940.

To all whom it may concern:

Be it known that we, CHARLES A. HANSON and ALBERT L. HANSON, citizens of the United States, residing at Munising, in the 5 county of Alger and State of Michigan, have invented a new and useful Land-Marker, of which the following is a specification.

Our invention relates to an improved land marker having novel characteristics 10 and advantages. Among the objects of our invention is the provision of a land marker which is indestructible so that in case of fires a re-survey will not be necessary, while at the same time not being of excessive 15 weight or costliness. An important object of our invention is the provision of a novel base member for such a land marker including a novel raised portion disposed on a median line through the base member, 20 whereby the marker is prevented from being turned unless it is taken up intentionally from its location. It is a further object of our invention to provide a novel cap member for such a land marker which may be 25 readily marked and which has direction indicating designations on the cap member there being a predetermined relation of such designating direction mark to the raised portion on the base member. It is 30 further our object to provide quarter designating markings on the cap member of suitable character. Another object of our invention is the provision of a novel construction whereby effectively to secure the 35 base member to the main stem of the marker to insure the permanence of the construction.

We attain the objects of our invention by the mechanism illustrated in the accompanying drawings, in which—

Figure 1 is a vertical section on line 1—1 of Fig. 3; Fig. 2 is a top plan of the cap member; Fig. 3 is a horizontal section on line 3—3 of Fig. 1 looking toward the base; 45 and Fig. 4 is a side view of the base member.

Like characters of reference designate like parts throughout the several views.

Referring to the accompanying drawings, 50 we provide an indestructible hollow stem 1, of galvanized pipe. The lower portion 3 of stem 1 is embedded in a cast base member 2. Portion 3 of stem 1 is provided with a converging annular flange 8 which is adapted to permanently secure the stem 1 to the 55 base 2. It will be observed further that

portion 9 of base 2 extends to a height within the stem parallel with the opposite raised portions 4, on base 2, as shown in Fig. 1. Raised portions 4 are disposed on a median 60 line of base 2, and are very important inasmuch as they prevent turning accidentally of the land marker. Without such means for obviating accidental shifting of the marker its usefulness is greatly impaired. 65 Secured to the top of stem 1 I provide a novel brass and copper cap member 5, having a hollow portion 6 engaging over the upper portion of stem 1, and secured thereto by a suitable metal fastening member 7, to 70 insure the permanence of the marking member. Cap member 5 is provided with novel designating markings 10 consisting of an arrow, four lines at right angles one of which terminates in the arrow, and an inner 75 circle from which the four lines radiate, whereby to divide the cap member into quarters. Suitable land marking designations differing in character for each individual marker may readily be stamped on 80 the respective quarter portions set off by the above described designation markings, inasmuch as the cap member is of brass. The construction disclosed makes it possible to provide land markers of light weight, which 85 may be readily transported; insures their permanence and obviates re-surveys in the event of fires; and prevents the accidental displacement of the land marker which would destroy its usefulness. Its operation 90 is apparent from the accompanying drawings, the base being embedded in the earth at the corner of a section, the projection or raised portions 4 preventing its turning. It is disposed with the arrow on the cap 95 member pointing toward the north. In consequence the section markings on the four quarters set off by the lines at right angles to each other are properly disposed to designate the respective sections. The cap 100 member being of brass suitable section markings as desired are readily inscribed by means of suitable stamping dies, the designation markings indicated by 10 on Fig. 2 only being claimed as our invention. The 105 marking being disposed on top of the cap member in an approximately horizontal position and not vertically, are readily examined by the surveyor or cruiser or forester.

What we claim is:

1. An indestructible land marker of light weight adapted to be readily transported by

hand, comprising a flat base, flanges on its upper portion, a tubular metal stem having bent ends embedded in the base, and a cap member having direction markings on its top riveted over the metal stem.

2. A light, easily-transported and permanent land marker comprising a metal cap bearing direction markings, a light tubular metal stem bearing the metal cap, and a flat base member adapted to be completely concealed beneath the surface of the ground and having upwardly projecting flanges to prevent the disturbing of the marker without unearthing the base member and leaving evidences of tampering.

3. A fireproof land marker comprising a direction marking cap member, a light galvanized pipe stem over which the cap mem-

ber is riveted, the pipe member terminating in a converging annular flange, a broad base member in which the aforesaid flange is embedded, the base member having opposite projections normally concealed beneath the surface of the ground and adapted to hold the marker against accidental displacement and to necessitate unearthing the base member to permit of turning the landmarker, whereby to prevent tampering with or disturbance of the landmarker without the leaving of evidences of such disturbance.

CHARLES A. HANSON.
ALBERT L. HANSON.
